(57) **CLAIM**

The ornamental design for forearm supporting device, as shown and described.

DESCRIPTION

FIG. 1 is a perspective view of a forearm supporting device in accordance with the invention;

FIG. 2 is a right side elevational view of the forearm supporting device of FIG. 1, the left side elevational view being a mirror image of the right side;

FIG. 3 is a top plan view of the forearm supporting device of FIG. 1;

FIG. 4 is a rear elevational view of the forearm supporting device of FIG. 1;

FIG. 5 is a bottom plan view of the forearm supporting device of FIG. 1; and,

FIG. 6 is a front elevational view of the forearm supporting device of FIG. 1.
